Mr. E. L. Garrison's Design for an Ornamental Banking Stone

*Exhibited at the 1851 Great
Exhibition of Manufactures from 1851*

Dec. 660

Harrison Eaton, of Nashua N.H.
Assignor to
James Hartshorn and Winslow Ames, of same place
Letters Patent No 660 Dated July 11 1854

The schedule referred to in these Letters Patent, and making part of the same

To all Persons to whom these presents shall come.

Be it known, that I, Harrison Eaton, of Nashua in the County of Hillsborough, and State of New Hampshire, have invented or produced a new ornamental design for a cooking stove; and I do hereby declare that the same is fully represented in the accompanying drawings of which.

The base mouldings of the side plates repose on feet as seen at E.E. and are composed of an ovolu or quarter round, a. a fillet b, an ornamental or fluted cavetto c., a fillet d., cavetto e., and a sloping fillet f. Above the base, the side is surrounded with a panel moulding g, and is surmounted by a cornice h. of the form in section as exhibited in Figures 2 and 3.

Each of the three doors I. G. H. has on its panel a star i. from four of whose points lance heads k. k. k. k. are extended; these points and the star being placed in a star panel or in another star l. placed within a radiated panel, m. a section of which is given in Figures 2 and 3. The top of the front and back plates are seen at I.K.L. while that of the hearth plate is seen at M. the form of its boundary mouldings being exhibited in Fig. 3. The form and ornamental character of each leg is given in the drawings; Figure 4, representing a transverse section of it. The horizontal section of the end of each end plate is simply a quarter round.

I claim the ornamental design for the side plates and its feet and that of each door as exhibited in the drawings.

In testimony whereof, I have hereunto set my Signature this Ninth day of June A.D. 1854
